UNITED STATES PATENT OFFICE.

LEWIS H. PFLEGHARDT, OF FAYETTE CITY, PENNSYLVANIA.

METALLIC TIE AND RAIL-FASTENER.

No. 833,545.

Specification of Letters Patent.

Patented Oct. 16, 1906.

Application filed July 2, 1906. Serial No. 324,341.

To all whom it may concern:

Be it known that I, LEWIS H. PFLEGHARDT, a citizen of the United States of America, residing at Fayette City, in the county 5 of Fayette and State of Pennsylvania, have invented certain new and useful Improvements in Metallic Ties and Rail-Fasteners, of which the following is a specification, reference being had therein to the accompanying 10 drawings.

This invention relates to certain new and useful improvements in metallic tie and rail-fasteners; and the invention has for its object to provide a simple and inexpensive metallic tie for rails whereby novel means is 15 employed in connection with the tie for firmly retaining the rails upon the tie.

The invention aims to dispense with the wood ties and sleepers commonly used upon 20 a ballasted road-bed, which are expensive to maintain and continually need renewing. In lieu of the wood ties I use metallic ties, which are especially constructed to take a firm grip in a ballasted road-bed and are provided with novel fasteners for retaining rails 25 upon the tie.

A particular feature of my invention resides in the rail-fastener, which can be easily and quickly placed in position, not necessitating the use of skilled labor.

My improved tie and rail-fastener dispenses with the spreading and displacement of rails and allows the rails to expand and contract where a joint occurs between two rails.

The detail construction of my improved tie and rail-fastener will be presently described and then specifically pointed out in the appended claims.

Referring to the drawings forming part of 40 this specification, like numerals of reference designate corresponding parts throughout the several views, in which—

Figure 1 is a perspective view of my improved tie and rail-fastener. Fig. 2 is a longitudinal sectional view of the same, and Fig. 45 3 is an enlarged perspective view of the rail-fasteners of a tie.

My improved tie is constructed of strong and durable metal and conforms to a channel-bar approximately the same length as the 50 wood ties in use. The channel-bar consists of side walls 1 1, a raised bottom plate 2, and a top plate 3. The raised bottom plate 2 is provided to form an oblong pocket 4 for the ballast of a road-bed, the depending sides 1 1 55 of the tie preventing the same from being dis-

placed when once embedded in the ballast of the road-bed.

The side walls 1 1 adjacent to the ends of the tie are cut away to provide rail-seats 5. 60 The sides 1 at the end of the tie are formed with integral fish-bars 6, adapted to embrace the outer sides of the rails 7, mounted upon the seats 5 of the tie.

The top 3 of the tie is cut away to provide 65 openings 8 for my improved rail-fastener, which will be presently described. The ends of the tie are partially closed by plates 9, which may be made a part of the bottom 2 or may be separate and suitably secured between the side walls 1 1 of the tie. These plates extend below the bottom plate 2 and are adapted to prevent the ballast from entering the tie, also preventing lateral displacement of the tie when used upon a road-bed. 75

My improved rail-fasteners consist of blocks 10, adapted to engage the inner sides of the web portions of the rail 7. The blocks 10 are provided with web portions 11, having depending lugs 12, said lugs being provided 80 with transverse openings 14, whereby the fasteners can be secured in the tie by bolts and nuts 15. The bolts are adapted to extend through the side walls 1 of the tie and be secured therein by a nut or bur, which 85 can be provided with a conventional form of nut-lock. (Not shown.)

When the tie has been properly positioned in a ballasted road-bed, the rails 7 are placed upon their seats 5 and the blocks placed in 90 engagement with said rails, whereby the web portions 10 of said blocks will extend into the openings 8, as clearly shown in Fig. 2 of the drawings.

Since the stresses and strains of rolling 95 stock passing over the rails have a tendency to spread the rails, I have provided the fish-bars 6, which embrace the entire outer side of said rails, while the fasteners serve to maintain the rails in engagement with said bars. 100 By the novel construction of my improved tie and rail-fasteners it will be impossible for vertical displacement of the rails to occur, inasmuch as the base portions of the rails are firmly held by the fish-bars 6 and the fasteners 105 10.

When my improved tie is rolled and afterward milled or machined, the top of the tie 3 may be made a separate and distinct piece, which can be placed in the tie after the same 110 has been rolled and properly machined.

My invention particularly resides in the

raised bottom of the tie and the novel fasteners which I employ in connection with the same.

It is obvious that such changes in the details of construction as are permissible by the appended claims may be resorted to without departing from the spirit and scope of the invention.

What I claim, and desire to secure by Letters Patent, is—

1. In a metallic tie and rail-fastener, the combination with rails, of a channel-shaped tie comprising side walls, a top, and a raised bottom plate, plates closing the ends of said tie and having depending extensions, the side walls of said tie being cut away to form seats for said rails, fish-bars carried by the side walls of said tie adjacent to its ends to embrace the outer sides of said rails, fasteners engaging the inner sides of said rails, and extending into said tie, bolts passing through the side walls of said tie and said fasteners,

and nuts retaining said bolts within said tie, substantially as described.

2. In a metallic tie and rail-fastener, the combination with the rails, of a channel-shaped tie comprising side walls, a top, a raised bottom plate, and end-closing plates, said side walls being cut away to provide rail-seats, fish-bars carried by said side plates to embrace the base and web portions of the rails, fasteners engaging the inner side of the rails and extending through openings in the top of the tie, securing bolts for said fasteners extending through the side walls of the tie and through the fasteners, and retaining-nuts for said bolts.

In testimony whereof I affix my signature in the presence of two witnesses.

LEWIS H. PFLEGHARDT.
